UNITED STATES PATENT OFFICE.

EDWARD L. GILLESPIE, OF SEATTLE, WASHINGTON.

IRONING-BOARD.

1,059,144.

Specification of Letters Patent.

Patented Apr. 15, 1913.

Application filed January 9, 1912. Serial No. 670,244.

To all whom it may concern:

Be it known that I, EDWARD L. GILLESPIE, a citizen of the United States, residing at Seattle, in the county of King and State of Washington, have invented certain new and useful Improvements in Ironing-Boards, of which the following is a specification.

This invention relates to improvements in ironing boards.

10 The object of the invention is the provision of an ironing board that may be concealed when not in use in a convenient receptacle in the wall of a room and may be yieldingly retained in such upright inoperative position without danger of becoming dislodged.

15 A further object of the invention is the provision of a device of the class described of relatively simple and practical construction and that is particularly serviceable and adapted to the uses for which intended.

20 The invention consists in the novel construction, combination and adaptation of an ironing board and attachments thereto, as 25 will be fully described in the following specification, illustrated in the accompanying drawings, and finally set forth in the appended claims.

25 In said drawings, Figure 1 is a front elevation partly broken away, of devices embodying my invention. Fig. 2 is a view in side elevation, partly in vertical section, of the same shown in upright vertical inoperative position. Fig. 3 is a similar view the 30 board being shown in lowered operative position. Fig. 4 is a cross sectional view on the line 4-4 of Fig. 2. Fig. 5 is an underside detail view of a portion of the ironing board.

35 Referring to the drawings, the reference numeral 1 designates a closet which may be secured to a wall or set therein, as shown in the views and consists of a rear wall 2, side walls 3, top and bottom walls 4 and 5, respectively, and may desirably be provided with a hinged door 6.

40 The numeral 7 denotes an ironing board pivotally connected at one end at 8 in proximity to the bottom of said closet and adapted to swing from an upright position, as 45 shown in Fig. 2, to a lower operative position, as shown in Fig. 3, wherein it is supported by a brace 9 formed of channel iron, preferably, having one end pivotally connected at 10 to the board somewhat forward of the middle of the board and has its oppo-

site end 9' pivotally connected to an end of a relatively light rod 11 that has its other end 12 slidably engaged in guideways 13 arranged longitudinally of the board and intermediate said connection 10 and the inner end of the board. Thus when the board is in its upright position, as in Fig. 2, the brace hangs vertically and the weight thereof forces the end 12 of said rod upwardly in 50 guideways 13 until the rod hangs nearly vertically and partially within the side flanges of said channel. As the board is inclined outwardly to bring the same down to operative position, the lower end of the brace 55 tends to fall outwardly to a vertical position but the rod 11 connection restrains such movement to the inclined position shown in Fig. 3 whereby, when the board reaches its 60 lowermost position, the lower end 9' of the brace contacts with a bracket fixture 14 which is positioned to receive same and prevent the marring of the woodwork or plaster 65 thereby. Centrally of said closet an upright post 15 is fixedly secured at top and bottom in sockets provided therefor. A set 70 collar 16 is mounted about said post and provided with a screw 17 impinging upon the post to secure the collar in any adjusted position. 18 designates a sliding collar therebelow upon said post and between the collars 75 is positioned a helical compression spring 19 coiled about said post and tending to urge the latter collar downwardly. Oppositely directed pins 20 on collar 18 afford pivotal 80 connections with links 23 whose lower ends are similarly connected to the upturned lugs 21 of straps 22 rigidly secured to the upper side of the head of the board. When said board is in upright inoperative position, as 85 in Fig. 2, the lugs 21 are in lateral alignment with said post and the links 23 are likewise in parallel alignment. The spring 19 is under sufficient tension through leverage 90 exerted upon said lugs to maintain said board in upright position. As the board is swung downwardly to working position, as shown in Figs. 1 and 3, said lugs describe an upwardly directed arc that further compresses the spring. At the outward termination of said arc the lugs rest at a point 95 somewhat past the center of the pivot 8 and hence the increased pressure afforded by the compression spring tends to maintain said board in its lowermost position. When 100 it is desired to raise the board again, the latter is lifted at its outward extremity for 105

a short distance whereupon the connection of the links 28 and said lugs is moved over the dead center and the power in the spring asserts itself to assist in the elevation of the 5 board and in maintaining the same, as described.

The board is desirably built within a closet 1 which may be inserted in the wall between the studding 24 either before or 10 subsequent to the construction of the house or it may be fixedly secured by screwing to a convenient wall of a room. As planned, said closet is provided with an extension therebelow in which is formed a sheet-metal 15 lined receptacle 25 for the reception of flat irons and the like.

The operation of the invention is believed to be sufficiently clear from the foregoing description and it may be said that the invention 20 is complete in its adaptation to the service intended and provides an exceedingly efficient and convenient addition to a domestic establishment.

While I have described at some detail the 25 embodiment of my invention shown, it is to be understood that I do not confine myself thereto as obviously changes in detail and modifications of parts may be made within the spirit of the invention, and the scope of 30 the claims, without sacrificing its advantages.

What I claim, is—

1. An ironing board comprising a board hingedly connected to be swung from a horizontal 35 to an upright position, an upright

post fixedly secured adjacent the inner end of said board, a movable collar on said post, a spring about said post urging the movable collar downwardly, and links connecting said movable collar to said inner end of said 40 board.

2. An ironing board comprising a board hingedly connected to be swung from a horizontal to an upright position, an upright post fixedly secured adjacent the inner end 45 of said board, a movable collar on said post, a spring about said post urging the movable collar downwardly, links connecting said movable collar to said inner end of said board, and a brace swingable to operative 50 position, as said board is lowered.

3. An ironing board comprising a board hingedly connected to be swung from a horizontal to an upright position, an upright post fixedly secured adjacent the inner end 55 of said board; a movable collar on said post, a spring about said post urging the movable collar downwardly, links connecting said movable collar to said inner end of said board, a brace adapted to swing outwardly 60 when said board is lowered, and a rod slidably connected at one end to the board and at the other end pivotally connected to the lower end of the brace.

Signed at Seattle, Wash., this 28th day of December 1911.

EDWARD L. GILLESPIE.
